UNITED STATES PATENT OFFICE.

ELIAS ABDO, OF PITTSBURGH, PENNSYLVANIA.

PAPER-BAG HOLDER.

1,315,272.

Specification of Letters Patent. Patented Sept. 9, 1919.

Application filed July 11, 1918. Serial No. 244,400.

To all whom it may concern:

Be it known that I, ELIAS ABDO, a citizen of the United States, and a resident of Pittsburgh, in the county of Allegheny and State 5 of Pennsylvania, have invented a new and useful Improvement in Paper-Bag Holders; and I do hereby declare the following to be a full, clear, and exact description thereof.

My invention relates to a device for holding paper bags, and has for its object to provide such a device which will hold different sizes of paper bags, as well as a quantity of each size, and will also enable any particular size bag to be removed when desired, 10 and allow bags of any of the sizes used to be placed within the device without interfering with, removing or withdrawing of the other bags.

To these ends my invention consists, generally stated, in the novel arrangement, construction and combination of parts, as hereinafter more specifically set forth and described and particularly pointed out in the claim.

To enable others skilled in the art to which my invention appertains to construct and use my improved device for holding paper bags, I will describe the same more fully, referring to the accompanying drawings, in which—

Figure 1 is a front view of my improved holder for paper bags;

Fig. 2 is a longitudinal central section of the same;

Fig. 3 is an enlarged side view of a portion of the holder;

Fig. 4 is a plan view of one of the holders removed; and

Fig. 5 is a detail section of one of the 40 cross-members.

Like symbols of reference herein indicate like parts in each of the figures of the drawing.

As illustrated in the drawings A represents my improved holder for paper bags, which is adapted to be hung from a suitable support and is preferably formed of thin sheet metal and provided with the channel-shaped upright or main supporting member 45

1. Pivotedly or hingedly connected to the upright member 1 by means of bolts 3 passing through the sides 2 of said member are a series of bag holding members 4, which are of different lengths and widths for holding the different size bags within the same, as hereinafter described. As shown and ar-

ranged on the member 1, these members 4 vary in size from the smallest one at the upper end of the member 1 to the largest one at the lower end of said member, and 60 when in their normal positions they overlap each other. These holders 4 are each provided with a body or back strip portion 5 which is adapted to fit within the upright member 1 and between the sides 2 of the 65 same when in its normal position. One end of each of the back portions 5, such as the upper end 6 is bent around its bolt 3, so as to form its pivotal or hinge connection therewith, and the other or lower end of said portion is provided with an outwardly extending portion 7 having an upwardly extending lip 8 at its outer end for supporting the lower ends of the bags. Extending across 70 each of the bag holders 4 are the cross members 9, which are formed of two L-shaped strips having two body portions 11 on the same formed with an angle or lip portion 10 extending forwardly at one of their outer ends for supporting the sides of the bags, 75 and the body portions 11 being adapted to have the bags rest on the same. The body portions 11 of the cross members 9 can be adjustably connected together and to the back strip portion 5 on the bag-holding 80 member 4 by means of a bolt 12 passing through slots 13 in said body portion and through a hole 13' in said back portion.

The upper or smallest bag holding member 4 is provided with a spring lip 14 which extends down from the hinged upper end 6 on the back strip portion 5 of said member for holding the bags contained in said member and which are placed under said lip and between the portion 7, lip 8 and lip portions 90 10. The other sizes of bags are contained 95 within the other bag holding members 4 and between the portions 7, lips 8 and lip portions 9 thereon and are held down in place by means of the weight of the bags and holding member above each of the same.

When the holder A is in use, it is hung upon a wall or other suitable support, such as by means of nails (not shown) passing through holes 15 at the upper and lower 105 ends of the supporting member 1, and when it is desired to remove one of the bags within any of the members 4, all that is necessary is to simply grasp the lower end of the bag and pull the same out from under the 110 member 4 and from the bags within the same, which are weighted down on the mem-

ber and bags from which the bag is being withdrawn. When it is desired to refill any of the bag holding members 4 or to remove any of the bags from any of such members, 5 other than the uppermost member, all that is required is to lift up the member with its contained bags from over the member desired to be filled or bags removed, while the uppermost member can be easily filled 10 by placing the bags under the spring lip 14, as hereinbefore described, and they can be removed by pulling out the same from under said lip, both operations being performed without the necessity of raising said members. 15

It will thus be seen that my improved device for holding paper bags is cheap, simple and efficient in its construction, operation and use, and will not only form a convenient device for the merchant, but will also be a handy device for use in the home. The device is strong and durable, will not get out of order, and is so formed that its parts can be easily and quickly adjusted 20 and arranged for packing for shipment and assembling.

It will be obvious that while my improved device for holding paper bags is shown and described as being hung and operated placed 30 in a vertical position, it can be used in other

positions and for other purposes, and various modifications and changes in the design and construction of the device may be resorted to without departing from the spirit of the invention or sacrificing any of its advantages.

What I claim as my invention and desire to secure by Letters Patent is:

A sheet metal device for holding paper bags, comprising a main channel-shaped 40 supporting member, a series of hinged bag-holding members on said supporting member, each of said bag-holding members having a body or back strip portion and a cross member formed of two strips adjustably 45 secured to said strip portion by a bolt and slot connection, each of said strips having forwardly extending lip portion at one of the outer ends for supporting the side edges of the bags, and an outwardly extending portion at the lower end of said back strip portion and below said cross-member and having an upturned flange portion for supporting the bottom edges of the bags. 50

In testimony whereof I, the said ELIAS 55 ABDO, have hereunto set my hand.

ELIAS ABDO.
